PLYWOOD CORE MACHINE

Oscar S. Bolling, Minneapolis, Minn., assignor to
 Mereen-Johnson Machine Company, Minneapolis, Minn., a corporation of Minnesota

Application December 22, 1945, Serial No. 637,085

6 Claims. (Cl. 144—279)

1

My present invention provides an improved and highly efficient machine for making sheets from relatively narrow strips, slats or blocks of wood, or similar material.

Machines of the present invention are used primarily for gluing together wooden strips or slats to produce composite wood panels that are suitable for various commercial uses, such as for plywood cores. In this connection, it will be understood that in the production of plywood, the composite panels or sheets produced by this machine will be secured between wooden veneer sheets by subsequent and additional operations and by use of additional machines or devices.

In the use of the improved machine of the present invention for producing composite sheets from strip or slat material, slats or strips having glue applied to one edge of each strip (and before the glue is dried or set) are placed upon the receiving or input end of the machine in properly assembled relation and are fed from thence through a heating zone while being maintained in tight edge-to-edge contact. The glue on the previously edge-glued pieces thus becomes dried and set under heat and pressure while the material is subject to feeding movements through the machine, and a composite sheet is thus delivered from the output end of the machine.

In the machine of my present invention, as in the machine of my prior Patent 2,366,588, heating of the previously edge-glued and assembled slats or strips of work material to set and dry the glue is accomplished by passing the said material between opposed heated plates and, as in the case of the machine of my said prior patent, the edge-glued strips of work material are maintained in tight edge-to-edge contact during their passage through the space between the heating plates by resistance to forward feeding action set up by squeezing pressure of the opposed hot plates on the material and by further resistance to forward feeding movements of the material set up by a pressure-breaking mechanism located after the hot plates and adjacent the output end of the machine. The machine of the present invention, however, involves a number of very important improvements over the machine of said prior patent, and which include the following, to wit:

a. The present invention provides an improved feeding mechanism for positively feeding and continuously delivering work pieces (slats, strips, or the like) to and through the space between the opposed hot plates and the subsequent pressure mechanism.

b. The present invention further provides an improved hot plate structure involving spaced walls and intervening heating units. In the preferred arrangement illustrated, the heating units are in the nature of steam-conducting heat

2

transfer conduits running in zigzag fashion between opposite walls of the hot plates, and comprising relatively-straight laterally-spaced portions or sections extending between opposite longitudinal edge portions of the hot plates and connected by elbows. In the preferred arrangement, the only joints in the heat transfer conduits are between the relatively-straight portions or sections thereof and the connecting elbows. 10 In accordance with the present invention, the said connecting elbows are located laterally outwardly of the marginal longitudinal edges of the hot plates, where they are readily accessible for the purposes of inspection, repair of the joints between the elbows and straight sections, and removal and replacement of the elbows or relatively-straight conduit sections connected thereto.

c. Still another important feature of the present invention has to do with the mounting of the feeding mechanism, hot plates, and the pressure mechanism following the hot plates, on, and the anchoring of the same to, a supporting frame structure. It will be understood that the resistance to feeding action of the material set up by the hot plates and the pressure devices following the hot plates produces powerful forces tending to separate the feeding mechanism from the hot plates and the hot plates from the pressure mechanism following the same. Heretofore, it has been the practice to anchor the several units independently to the supporting frame structure to prevent longitudinal movements thereof with respect to the frame and to one another, and in so doing the powerful forces tending to separate the feeding mechanism from the hot plates and the hot plates from the pressure mechanism following the same was absorbed entirely through the frame structure, with the result that the supporting frame structure was placed under powerful stresses and strains tending to buckle and warp the same, and tending to produce misalignment between the feed mechanism, hot plates, and pressure mechanism following the hot plates. In accordance with the present invention, I overcome this tendency of prior art machines to buckle and warp the frame structure by connecting the successive cooperating units comprising the feed mechanism, hot plates, and pressure mechanism following the hot plates, together in a tandem relationship, whereby the forces tending to separate the said successive units of the machine are absorbed within the units themselves and independently 50 of the supporting frame structure. This important feature of the invention will be clarified and amplified later on in the specification and under the heading "Operation."

d. The present invention further provides a 60 novel and improved transmission mechanism in-

termidate the prime mover or motor and the feed mechanism, whereby to permit free vertical movements of the upper unit of the secondary feed mechanism with respect to the lower unit thereof when both are driven through common endless belts.

e. The present invention still further provides a novel automatic work-actuated control mechanism for the work feeding mechanism, whereby the feeding mechanism is automatically disrupted whenever the rate of delivery of work pieces to the secondary or positive feed portion of the feed mechanism fails to equal the rate of feed of the said secondary or positive feed portion of the feed mechanism. This feature is highly important in that it prevents operation of the positive feed portion of the feed mechanism under conditions when the frictional contact area between said feed mechanism and the work is reduced to a point where slippage will occur between the feed mechanism and work, and which slippage, if allowed, would be apt to damage and deface the work.

f. The present invention still further provides an improved mechanism for variably adjusting the pressure of the upper hot plate on the work.

The above and other highly important objects and advantages of the present invention will be made apparent from the following specification, claims, and appended drawings.

In the accompanying drawings, like characters indicate like parts throughout the several views.

Referring to the drawings:

Fig. 1 is a front and side perspective view of a plywood core machine embodying the improvements of my invention;

Fig. 2 is a plan view of the machine of Fig. 1;

Fig. 3 is an enlarged longitudinal sectional view taken on the line 3—3 of Fig. 2, and having some parts broken away;

Fig. 4 is a fragmentary view in side elevation taken on the line 4—4 of Fig. 2;

Fig. 5 is a fragmentary view in elevation taken on the line 5—5 of Fig. 2, and with some parts broken away;

Fig. 16 is a fragmentary view on an enlarged

scale taken approximately on the line 16—16 of Fig. 9;

Fig. 17 is a fragmentary perspective view on an enlarged scale of one of the secondary feed chains; and

Fig. 18 is a diagrammatic view illustrating the electrical hook-up of the feed mechanism.

The supporting frame of the machine described is made up in three sections indicated by 1, 2, and 3 respectively. The frame section 1 is at the input end of the machine and comprises laterally-spaced longitudinally-extending beams 4 and supporting legs 5 and 6. The legs 6 are rigidly tied together by cross-beams 7 and the inner ends of the beams 4 are rigidly anchored to the said legs 6; the outer ends of the said beams 4 being rigidly tied together by a transverse tie-plate 8. The intermediate frame section 2 comprises a laterally-spaced pair of longitudinally-extending plates 9 extending between and rigidly tying together the frame sections 1 and 3. The frame section 3, which extends to the output end of the machine, comprises laterally-spaced longitudinally-extending beams 10 and legs 11 and 12; the legs 12 being connected by transversely-extending beams 13 (see Fig. 5).

Mounted on the primary frame section 1 is a primary feed mechanism comprising laterally-spaced endless link belts or chains 14. These link belts or chains 14 run over wheels in the nature of pulleys 15 and wheels in the nature of sprockets 16. The several pulleys 15 are all journaled on an idler shaft 17 that is mounted fast in frame beams 4. The several sprockets 16 are all mounted fast on a shaft 18 that is journaled in bearing flanges 19 that project one from each of several inverted U-shaped chain guide rails 20. The chains 14 run over and are supported by a table 14a rigidly secured to the frame beams 4 (see Figs. 1, 2, 3, and 9).

The primary feed chains 14 feed stock to a secondary stock-feeding mechanism comprising a laterally-spaced series of lower endless feed belts or chains 21 and a laterally-spaced series of upper endless link feed belts or chains 22. At the input end of the secondary stock-feeding mechanism, the endless feed belts or chains 21 run over wheels in the nature of pulleys 23, and the endless feed belts or chains 22 run over similar pulleys 24. The pulleys 23 are all journaled on the shaft 18. The several pulleys 24 are each journaled on a different stub shaft 25, and each of the stub shafts 25 is individually mounted fast on a different arm 26 of a floating frame structure immediately to be described. The said floating frame structure comprises the said arms 26 and a tie-bar 27 (see Figs. 1, 2, and 3). The floating frame arms 26, of which there are several, extend in laterally-spaced parallel relation longitudinally of the machine, and the said tie-bar 27 is bolted or otherwise rigidly secured to the ends of said arms closest to the input end of the machine (see particularly Fig. 2). The other ends of said floating frame arms 26 are journaled on a rotary shaft 28 (see particularly Figs. 2 and 7). The several endless feed belts or chains 22 run over the pulleys 24 and also run over wheels in the nature of sprockets 29 that are mounted fast on shaft 28. The shaft 28, as will be seen by reference particularly to Figs. 2, 3, 7, 8, and 9, besides being intermediately journaled in the end portions of

the several frame arms 26, are journaled adjacent their opposite end portions in bearing bosses 30 of draw bars 31. The shaft 28 is anchored to the frame legs 6 by anchor links 31' that are pivotally mounted on said frame legs 6 at 31'' and to radial flanges on the draw bar hubs 30 at 30'. The shaft 28, intermediate its ends, is further journaled in bearing bosses 30 of additional draw bars 31^a (see particularly Fig. 2). The mounting of the other ends of the draw bars 31 and 31^a is important, and will be dealt with in detail later on. The lower endless belts or chains 21 run over the said pulleys 23 and sprockets 32, that are mounted fast on a power-driven rotary shaft 33. The power-driven rotary shaft 33 is journaled adjacent its opposite ends in bearings 34 on the supporting frame section plates 9 described (see particularly Fig. 7). Also, this power-driven shaft 33 is journaled intermediate the bearings 34 in the free end portions of rigidly-anchored draw arms 35, the importance of which will be emphasized later on.

The endless conveyor belts or chains 14, 21, and 22 are all driven from a suitable source of power, such as an electric motor 36, through power transmission connections comprising a chain 37 running over a sprocket 38 on the shaft of motor 36 and a speed-reducing sprocket 39 on a transverse shaft 40 journaled in suitable bearing brackets 41 on beam 10 (see particularly Figs. 3 and 4). A shaft 42 is journaled adjacent its ends in the frame plates 9 and is driven at reduced speed from the shaft 40 by a pair of endless link chains or belts 43 running over sprockets 44 fast on the shaft 40 and sprockets 45 fast on shaft 42. Shaft 33 is driven from the shaft 42 at reduced speed through pinions 46 fast on the opposite end portions of shaft 42 that mesh with gears 47 fast on opposite end portions of shaft 33 (see Figs. 4, 7, and 8). The shaft 28 is driven from the shaft 42 through chains 48 (see Figs. 4 and 7) running over sprockets 49 fast on opposite end portions of shaft 42, idler sprockets 50 journaled on a pair of stub shafts 51 that are mounted fast each on one of the plates 9, sprockets 52 mounted fast on opposite end portions of shaft 28, and yieldingly-biased pick-up sprockets 53. The pick-up sprockets 53 are idlers and are journaled on the free end portions of arms 54 that are pivoted at 55 to opposite frame beams 10, and which are yieldingly-biased in directions to take up the slack in chains 48 by adjustable tension springs 56 (see particularly Fig. 4). The primary feed chains 14 are driven from shaft 33 by a chain 57 running over a sprocket 58 fast on shaft 33 and a speed-increasing sprocket 59 fast on shaft 18. It will be seen that the above described transmission mechanism drives the chains 21 and 22 at like speeds and drives the chains 14 at a somewhat increased speed with respect to the chains 21 and 22. It will also be seen that the difference in speed between pulleys 23 on shaft 18 and sprockets 59 on shaft 18 is compensated for by free rotation of the pulleys 23 on the shaft 18 (see Fig. 9).

The lower portions of chains 21 run through the inverted U-shaped guide rails 20 and the upper portions of said chains 21 are supported by and run over the upper surfaces of said inverted U-shaped guide rails 20. The lower chain-engaging portions of the chains 22 intermediate the pulleys 24 and sprockets 29 are yieldingly-pressed downwardly by hold-down shoes 60 and coil compression springs 61 interposed between

each hold-down shoe 60 and a longitudinally extended pressure bar 62. The springs 61 are telescoped over small bosses on the hold-down shoes 60 and corresponding bosses on the under surfaces of pressure bars 62. The pressure bars 62 each extend in closely-spaced parallel relation to a different floating frame arm 26, and these are held against longitudinal sliding movements by stop lugs 63 projecting from said arm 26. The hold-down shoes 60 and pressure bars 62 are confined between their respective cooperating floating frame arms 26 and retainer plates 64 that are anchored to their respective cooperating floating frame arms 26 by stud bolts 65 passed therethrough and threaded into bosses 66 on the floating frame arms 26 (see particularly Figs. 3 and 10). The bosses 66 adjacent the extreme ends of retainer plate 64 serve as stop lugs to limit longitudinal movements of the several hold-down shoes 60. The pressure bars 62, which are yieldingly-pressed upwardly by coil springs 61, bear against a pair of upwardly-extended pressure legs 67 that are channeled, as shown best in Fig. 10, to receive the upper portions of the bars 62. By reference particularly to Figs. 3, 7, and 10, it will be seen that the upwardly-extended pressure legs 67 are formed with transversely-extended passages 68 to receive the upper portions of link belts or chains 22. The pressure legs 67 are connected to the under surfaces of a pair of transversely-extended bridge beams 69 by screw-threaded pressure-adjusting studs 70. These pressure studs 70 are provided with diametrically-reduced upper end portions that work loosely through apertures in the lower flanges of the bridge beams 69, and are provided near the lower extremities of said diametrically-reduced portions with stop shoulders 71 that engage the under surfaces of said beams 69 and limit upward movements of the studs 70 therethrough. The screw-threaded lower portions of the studs 70 are screw-threaded directly into the pressure legs 67, as shown best in Figs. 3, 7, and 10, and are locked in adjusted positions by lock nuts 72. The bridge beams 69 are vertically adjustably supported from the frame legs 6 (see Figs. 4, 7, and 8) by upstanding screw-threaded shanks 73 on legs 6, nut-acting worm gears 74 screw-threaded on the shanks 73, and gear boxes 75. The upper ends of the shanks 73 work loosely through the lower flanges of the beams 69, and the nut-acting worm gears 74 are journaled within the gear boxes 75. The nut-acting worm gears 74 are operated externally of the gear boxes 75 by operating mechanism comprising a driven shaft 76 within the gear box and journaled in the end portions thereof, worms 77 on the shafts 76 and meshing with the worm teeth of the nut-acting worm gears 74, bevel gears 78 fast on shafts 76, and intermeshing bevel gears 79 on an operating shaft 80 that is journaled in bearing flanges 81 (see Figs. 1, 2, 7, and 8) and is equipped with an operating wheel 82. From the above, it will be clear that the amount of yielding pressure exerted on the work, indicated by Y, through the lower runs of the chains 22, springs 61, pressure bars 62, and pressure legs 67, may be adjustably varied by rotation of the hand wheel 82. Before going further, it is desirable to call attention to the fact that the work Y is in the nature of a plurality of strips extended transversely of the machine and brought into edge-to-edge contact, and that the receiving end portion of the floating conveyor or feed unit comprising pulleys 24, 75 sprockets 29, and chains 22, is limited against

downward movements by hanger bolts 83 that are threaded into and project upwardly from the floating frame arms 26 and work loosely through brackets 84 projecting from beams 69 (see Figs. 1 and 3). Downward movements of the floating upper conveyor unit comprising chains 22 are adjustably limited by nuts 85 on the upper ends of hanger bolts 83, and which normally are spaced above the brackets 84. The object of these nut-equipped hanger bolts 83 is to maintain a predetermined spacing less than the thickness of the work between the cooperating lower and upper chains 21 and 22 respectively in the absence of work strips Y therebetween, so that strips Y may be readily fed into the space therebetween. It is also desirable to call attention to the fact that the feed chains 21 and 22 are provided on their work-engaging faces with gripping teeth, as shown best in Fig. 17, which is a perspective view respective of both of the chains 21 and chains 22. The secondary feed mechanism comprising the chains 21 and 22 feeds strips of work material Y between upper and lower hot plates 86 and 87 respectively. These hot plates 86 and 87, as shown, are made up of three similar sections rigidly connected together as at 88 (see Figs. 2, 3, and 12). Each section of each of the hot plates 86 and 87 comprises a flat metallic work-engaging wall 89, a backing wall 90, and an intervening heating element 91. The heating element of each section of each of the hot plates 86 and 87 is in the nature of a heat transfer conduit comprising laterally-spaced parallel portions extending transversely of the hot plates and connecting elbows 92 that are located laterally outwardly of the marginal edges of the walls 89 and 90 of their respective hot plate sections (see Figs. 2 and 16). Preferably, the laterally-spaced parallel sections and connecting elbows of the heat transfer conduits 91 are formed of cross-sectionally square seamless tubing providing maximum heat transfer efficiency between the conduits and work-engaging heat transfer plates 89. Preferably, also, the elbows 92, shown best in Fig. 16, are welded or brazed to the ends of the straight sections of the conduits 91 at points outwardly of the marginal edges of the hot plates, where the joints are readily accessible at all times for inspection and repair. Preferably, the otherwise exposed elbows 92 are covered by guard channels 93 suspended by brackets 94 (see Fig. 11). The work-engaging heat transfer plate 89 and the backing plate 90 of each hot plate section are rigidly, but detachably, connected together by stud bolts 95 passing through the walls 90 and screw-threaded into bosses 96 projecting from the walls 89 (see Fig. 12).

The lower hot plate 87 is slidably seated on transverse cross members 97 on longitudinal frame beams 10 through the medium of shoes 98 rigid on the backing walls 91 of the lower hot plate. Lower hot plate 87 is anchored at its receiving end to the sprocket shaft 33 by means of the before-mentioned draw arms 35, which draw arms are journaled on the shaft 33 and rigidly anchored to the work-engaging wall 89 of the lower hot plate by cap screws or the like 99 threaded into bosses 100 projecting from and rigid with the wall 89 (see Figs. 3, 8, and 9). The lower draw arms 35 are equal in number to, and located directly below, the draw arms 31 and 31^a of the upper hot plate 86.

The upper hot plate 86 normally rides on and is maintained under pressure against the work strips Y in a manner hereinafter described, but

is held against bodily movements longitudinally of the machine by the before-described draw links or bars 31 and 31^a, which are pivotally anchored at their outer ends to the shaft 28, and which are pivotally anchored to the work-engaging wall 89 of the upper hot plate 86 at 101 through the medium of upstanding anchoring flanges or brackets 102 that are bolted or otherwise made fast to the wall 89 by cap screws or the like 103. 10 Of course, it will be clear that the links or bars 31 and 31^a, being pivoted at both ends, permit free vertical movements of the upper hot plate 86. 15 Mounted on the upper hot plate 86 is a superstructure comprising a laterally-spaced pair of longitudinally-extended beams 104 that are clamped to a plurality of underlying transverse beams 105 by clamping gibs 106, shown best in Fig. 11, whereby to permit free movements of the beams 105 with respect to the beams 104 as a 20 result of expansion and contraction of the upper hot plate 86, to which the said beams 105 are anchored in a manner immediately to be described. With reference particularly to Fig. 11, it will be seen that the beams 105 are provided with legs 107 having outturned feet 108, and it 25 will be further seen that springs 109 are interposed between the feet 108 and the upper hot plate, whereby to transfer the weight of the superstructure to the upper hot plate 86. The superstructure is positively anchored to the upper hot plate by nut-equipped bolts 110 screw-threaded into transverse ribs 111 of the upper hot plate 86 and passed upwardly through the springs 109 and feet 108 with the nuts thereof applied above 30 said feet 108. At this point, attention is incidentally called to the fact that the supporting brackets 94 of the projecting channels 93 are anchored directly to the legs 107, as shown best at 112 in Fig. 11. The transverse ribs 111 may 35 be assumed to be welded or brazed directly to the work-engaging heat transfer wall 89 of the upper hot plate 86.

The weight of the above-described superstructure will provide a minimum operating pressure 40 on the upper hot plate 86, but for producing additional pressure and for raising the upper hot plate and its superstructure, I provide a pressure-adjusting and lifting mechanism immediately to be described. This adjusting and lifting mechanism comprises a pair of transversely-extended shafts 113 located adjacent opposite ends of the superstructure beams 104 and over opposite end portions of the upper hot plate 86. These shafts 113 are each journaled at one end in a bearing block 114 carried by the under surface 45 of one of the beams 104 (see Fig. 3) and at its other end each of said shafts 113 is journaled in a gear case 115 carried by and secured to the under surface of an opposite beam 104. At their extreme outer ends, the shafts 113 are provided 50 with cranks 116 that may be assumed to be keyed thereto for common rotation therewith. The several cranks 116 are connected by rigid links 117 to frame beams 10 through the medium of anchoring brackets 120 and nut-equipped bolts 121. For operating the several cranks 116 and their respective shafts 113 in unison and 55 from a common operating point, I provide an operating mechanism comprising worm gears 122, cooperating worms 123, a longitudinally-extended

operating shaft 124, a ratchet gear 125 fast on shaft 124, an operating lever 126 having a bifurcated end journaled on the shaft 124, and a reversible ratchet 127 (see Figs. 2, 5, and 14). The worm gears 122 are mounted fast on their respective shafts 113 each within a different gear case 115, and the worms 123 are mounted fast on shaft 124 each within one of the gear cases 115 and meshing with a cooperating worm gear 122. The reversible ratchet mechanism described is of well-known construction, not requiring further description, particularly in view of the fact that a hand wheel or other operating means could be substituted therefor for operating the shaft 124 in two directions. It will, however, be understood that operation of the shaft 124 in one direction will result in lifting of the upper hot plate 86 free of the work strips Y and that operation thereof in the other direction will place the rigid links 117 under tension to compress the several springs 109 to adjustably increase the pressure exerted on the upper hot plate 86 and by said plate 86 on the interposed work strips Y.

Before going further, it is desired to call attention to the fact that suitable heating medium, preferably steam, is introduced at the input end portions of the upper and lower hot plates 86 and 87 respectively by steam pipes 86' and 87' respectively, and which are respectively connected to the ends of heat transfer conduits 91 of the upper and lower hot plates (see Fig. 4). Also, by reference particularly to Fig. 5, it will be seen that the steam is returned to the source or exhausted to atmosphere, as desired, through conduits 86'' and 87'' leading from the opposite ends of the heat transfer conduits 91 of the upper and lower hot plates respectively, and which are located at the output ends of said conduits. Now, by particular reference to Figs. 2 and 5, it will be seen that the sections of the heat transfer conduits 91 serving adjacent sections of the upper and lower hot plates 86 and 87 are connected in series by connecting elbows 128.

For the purpose of guiding the work strips Y into the space between the upper and lower hot plates 86 and 87, and which space will be somewhat less than the thickness of the work strips Y when the said space is free of work strips, I provide at the input ends of the hot plates outwardly and forwardly-extending cam shoes 129. There are several of these cam shoes 129 rigidly secured to and projecting forwardly from the input edge of each of the hot plates 86 and 87 (see Figs. 9 and 16 particularly), and which operate as upper and lower pairs; each cooperating upper and lower pair of cam shoes 129 being provided with a reversely-flared cam-acting end, whereby to receive the work strips Y and guide the same into the space between the upper and lower hot plates. The cam shoes 129 further act to prevent the work strips Y from buckling in the space between the output end of the secondary feed mechanism and the hot plates, particularly when the work strips are very narrow in width.

In machines of this character, it is highly desirable that the edge-glued work strips Y be maintained under relatively very great edgewise squeezing pressure during their passage through the hot plates 86 and 87, and, therefore, for further increasing the edgewise squeezing pressure on the work strips as they pass through the hot plates, I provide adjacent the output end of the machine and beyond the hot plates 86 and 87 a friction-retarding mechanism comprising

short longitudinally-extended skid rails 130 below the work strips Y and cooperating pressure shoes 131 above the moving work strips Y, which latter will, by the time they reach the output end of the machine, be united into a unitary sheet. There are a laterally-spaced series of the longitudinally-extending skid rails 130 that are rigidly anchored to and project from the output end of the lower hot plate 87, and these extend over and rest upon transverse beams 13, and on which beams the skid rails 130 are free for longitudinal sliding movements as a result of expansion and contraction of the lower hot plate. Pressure shoes 131, of which there are a laterally-spaced series, are anchored to the output end portion of the upper hot plate 86 by leaf springs 132 (see particularly Figs. 5 and 15). By reference particularly to Fig. 15, it will be seen that the leaf springs 132 are each connected at one end to the intermediate portion of a pressure shoe 131 and are each rigidly connected at the opposite end thereof by a bolt 134 and a key 135 to a transverse rib 133 that is mounted fast on the heat transfer wall 89 of the upper hot plate 86.

For the purposes of lifting the pressure shoes 131 out of engagement with the work and out of the path of travel of the work, and for applying varying degrees of downward pressure thereon, I provide a mechanism comprising transverse beams 136 and pressure rods 137. The transverse beams 136 are connected at their bottoms by a plate 138, and are vertically adjustably supported from legs 12 through the medium of screw-threaded studs 139 and nut-acting worm gears 140. The screw-threaded studs 139 have reduced diameter portions extended through the upper ends of the legs 12 and clamped thereto by nuts 141. The nut-acting worm gears 140 are threaded on the studs 139 within gear boxes 143 attached to the under surfaces of opposite end portions of beams 136. By reference particularly to Fig. 5, it will be seen that the nut-acting worm gears 140 are provided with bearing hubs journaled in opposite walls of the gear boxes 143. The nut-acting worm gears 140 are all operated in unison from a hand wheel 144 through driving connections comprising a long transverse shaft 145 journaled in bearing bosses or brackets 146 projecting from opposite gear boxes 143, bevel gears 147 mounted fast on shaft 145, cooperating bevel gears 148 fast on shafts 149, and worm gears 150. The shafts 149 are each journaled at opposite end portions in an opposite gear box 143 and the worm gears 150 are mounted fast on their respective shafts 149 and mesh each with a different worm gear 140 (see Figs. 2, 5 and 6). The pressure rods 137 are anchored fast at their lower ends each to a different pressure shoe 131 and all project upwardly through the beam-carried plate 138 (see Fig. 5). The pressure rods 137 work loosely through the plate 138 and are provided below the plate 138 each with a compression spring 151. The springs 151 are compressed between the plate 138 and nuts 152 on said rods. For the purpose of limiting relative downward movements of the pressure rods 137 through the plate 138, suitable stop nuts or the like 153 are provided on the upper end portions of said rods 137. From the above, it will be clear that the amount of pressure exerted by the pressure shoes 131 on the work may be adjustably varied at will by manipulation of the hand wheel 144, which may also be manipulated to elevate the pressure shoes 131 out of the path of travel of the work, if and when de-

sired. Also, it should be noted that the frictional pull of the work on the pressure shoes 131 is transmitted to the upper hot plate in a substantially straight line through their respective anchoring leaf springs 132, which relieve the pressure rods 137 entirely of strain in a horizontal direction.

In practice, it has been found that if the feed chains 21 and 22 be permitted to operate faster than material is being delivered to the chains 14 and by the chains 14 to said chains 21 and 22, the chains 21 and 22 will start slipping on the work after the last work piece Y has advanced to some indefinite point intermediate the ends of the chains 21 and 22 depending upon the amount of pressure applied to the work by the hot plates 86 and 87 and hold down shoes 131. Such slippage between the chains 21 and 22 and the work pieces Y is, of course, objectionable because such slipping is apt to deface the work. It will be noted, however, that slippage occurring between the primary feed chains 14 and the work strips Y, because of the greater speed of travel of said feed chains 14, is permissible because of the relatively smooth upper surfaces of said feed chains 14 and relatively light weight of said work strips Y. To prevent such damaging slippage between the chains 21 and 22 and the work, it is highly important that work strips Y be fed by the chains 14 to the space between the cooperating chains 21 and 22 at a rate equal to or faster than the rate of delivery by the chains 21 and 22, so as to maintain a maximum area of frictional driving contact between the chains 21 and 22 and the work during all operating periods of said chains 21 and 22. To this end, I provide a pair of work strip-operated switches 154 above the chains 14 and ahead of the chains 21 and 22. These switches 154 are mounted on the transverse tie-bar 27, and each comprises a casing 155, a work-engaging arm 156 pivoted to its respective housing 155, a pair of fixed contacts 157, and a bridge contact 158 carried by the free end of an arm 159 that is rigidly anchored to the pivoted end of its cooperating lever or arm 156. The arms 156 and 159 form bell cranks and may be assumed to be gravity actuated toward switch-open positions. By reference particularly to Figs. 9 and 18, it will be seen that the free ends of the bell crank arms 156 normally ride on the upper surface of the work strips being fed to the space between the chains 21 and 22, and by reference to Fig. 18, it will be seen that the work strips Y keep the bell cranks in switch-closed positions, and by reference to Fig. 18, it should be obvious that when there is an absence of work strips Y under the free ends of the bell crank arms 156, that the said bell cranks will be moved by gravity to switch-open positions, not shown. The switches 154 operate in conjunction with a relay switch 160 to automatically control operation of the feed mechanism driving motor 36 in the following manner: By reference now to the diagram of Fig. 18, it will be seen that the motor 36 is operated from a three-phase power line 161 through leads 162, 163, and 164, which respectively have interposed therein spaced fixed switch contacts 162', 163', and 164' of the relay switch 160. The said relay switch 160 further comprises a solenoid winding 166 and a solenoid plunger 167 carrying bridge contacts 162'', 163'', and 164'' for cooperation respectively with pairs of spaced contacts 162', 163', and 164'. The said relay switch 160 also embodies a pair of fixed switch contacts 168 and a cooperating plunger-carried bridge contact 169. The relay switch 160 is of the type

that is yieldingly biased by gravity or otherwise toward open position, and from an examination of Fig. 18, it will be clear that when the relay switch 160 is closed by energization of the solenoid coil 166 thereof that the leads 162, 163, and 164 to the motor 36 will be completed and the motor rendered operative. The solenoid coil 166 of the relay switch 160 is initially energized to close switch 160 by a starting circuit comprising a lead 170 extending from a point in lead 163 ahead of switch 160, a short lead 170', a manually-closed self-opening starting switch 171, a lead 172, coil 166, and a lead 173 extending to lead 164. Momentary closing of the above-described starting circuit results in closing of all of the contacts of relay switch 160, thereby rendering the motor 36 operative and establishing a holding circuit for the solenoid coil 166; the latter, however, being dependent upon closing of the switches 154 by work pieces Y. This holding circuit comprises lead 170, a manually open self-closing switch 174, a lead 175, switches 154, a lead 176, now closed contacts 168 and 169 of relay 160, a lead 177, part of lead 172, relay coil 166, and lead 173. The manually open self-closing switch 174 is used to break the holding circuit and render the relay switch 160 and motor 36 inoperative independently of work strip-operated switches 154.

Operation

Preparatory to feeding strips of work material Y to the upper and lower hot plates 86 and 87, steam or other suitable heating medium will be passed through the heat transfer conduits 91 of the hot plates for sufficient time to bring the said hot plates up to the desired temperature. Before starting the feeding mechanism comprising feed chains 14, 21, and 22, a plurality of work pieces Y will be assembled on the now stationary feed chains 14 of the primary feed mechanism, and this primarily-assembled unit of work pieces will be pushed forwardly over the feed chains 14 under the work-actuated switches 154, thereby closing said switches 154. The machine is now ready for operation and the feed mechanism thereof will be set in motion by momentarily closing the manually-closed, self-opening switch 171, which may be assumed to be conveniently located on the machine. (For a detailed description of the hook-up of the electric motor 36, switches 154, relay switch 160, and switches 171 and 174, see the foregoing part of the specification.) With the feed chains 14, 21, and 22 now in operation, the work strips Y, manually placed upon the primary chains 14, will be fed to the space between lower and upper chains 21 and 22 respectively, and will be positively fed by the upper and lower secondary feed chains 21 and 22 to and through the space between the hot plates 86 and 87 and into and through the spaces between the final pressure mechanism comprising the skid rails 130 and the cooperating pressure shoes 131. It will, of course, be understood that work strips Y will be continuously placed upon the primary feed chains 14 for continuous delivery to the feed chains 21 and 22. In this connection, it is important to bear in mind that the primary feed chains 14 are driven at a somewhat greater speed than are the feed chains 21 and 22 of the secondary feed mechanism, so as to produce a continuous, although not great, slippage between the chains 14 and the work strips, which will maintain the work strips or pieces Y in compact edge-to-edge contact for delivery to the feed chains 21 and 22.

It will, of course, be understood, that the work strips or pieces placed upon the primary feed chains 14 will have had glue or other heat-drying adhesive previously applied to the edges thereof. As the edge-glued strips or work pieces Y are passed between the upper and lower hot plates 86 and 87 respectively, they will be subject to a relatively high temperature for a sufficient period of time to completely set and dry the glue while they are being maintained under edge-wise crowding pressure one against the other as a result of the frictional resistance to forward feeding movements of the work set up by pressure exerted on the work by the hot plates themselves and by further resistance to feeding movements set up by the final pressure mechanism comprising the skids 130 and the cooperating shoes 131. The work strips, thus being united while passing between the hot plates, are delivered from the pressure shoes 131 at the output end of the machine in a continuous sheet which will be cut into desired lengths by a subsequent machine. As previously indicated in the body of the specification, the pressure exerted by the pressure shoes 131 and the hot plates 86 and 87 on the work may be adjusted, through mechanism described, to place the work Y under the desired edgewise pressure during its passage between the hot plates, and the pressure exerted by the chains 21 and 22 on the work may be adjusted, in the manner described, to obtain sufficient driving traction to positively overcome the resistance to feeding movements set up by the hot plates and the final feeding mechanism involving skid rails 130 and pressure shoes 131.

As indicated in the introduction, a very important phase of the present invention is the manner in which the secondary or positive feed portion of the feed mechanism, upper and lower hot plates, and the pressure mechanism 130-131, are mounted and anchored. In this connection, attention is directed to the fact that the lower unit of the secondary positive feed mechanism, and which comprises chains 21, pulleys 23, and sprockets 32, is anchored directly to the supporting frame structure through the medium of shafts 18 and 33 and flanges 19 on U-shaped members 20 and the intermediate frame side plates 9 respectively. The upper unit of the secondary or positive feed portion of the feed mechanism, and which comprises feed chains 22, pulleys 24, and sprockets 29, is free for vertical movements and normally rests upon the surface of the work, but is anchored against longitudinal movements with respect to the supporting frame by the rigid links 31'. With these facts in mind, attention is again directed to the fact that the lower hot plate 87 is free floating on the underlying frame structure and is connected at its input end portion to the shaft 33 of the secondary feed mechanism through the draw arms 35, so that the forces tending to push the lower hot plate 87 longitudinally with respect to the driving mechanism are transmitted directly to the delivery end portion of the feed mechanism through a tandem, substantially straight line connection through draw bars 35 independently of the supporting frame structure. In a like manner, the upper hot plate 86, which floats upon the work, is connected in tandem to the output end portion of the upper unit of the secondary feed mechanism comprising chains 22 through draw bars 31 and 31a that connect directly to the shaft 28. Hence, the tendency of the upper hot plate to be moved longitudinally

of the machine and with respect to the chains 22, is absorbed through the draw bars 31 and 31a independently of and without placing any stresses or strains upon the supporting structure. 5 As we go to the output end of the machine, we note that the final pressure mechanism comprising the skid rails 130 and the pressure shoes 131 also is anchored indirectly to the positive feed mechanism by being connected to the delivery 10 end of the hot plates, whereby the tendency of the rails 130 and shoes 131 to be moved longitudinally of the machine by frictional engagement with the work is transmitted back to the source of pressure independently of the frame 15 structure and without producing any strains or stresses thereon. In other words, with the arrangement illustrated, a frictional load of the work on the pressure plates and final pressure mechanism respectively is taken through straight 20 line connections to the source of driving energy independently of the frame structure and without any tendency to warp or buckle the same. Obviously, this important feature permits the use of lighter framing and substantially eliminates any likelihood of the successive cooperating 25 elements of the machine being thrown out of proper working alignment.

It will be noted by reference to Fig. 10 that the hold down shoes 60 are provided with laterally-extended flanges 60' that are contained within guide recesses 26' and 64' of the floating frame arms 26 and the retainer plates 64 respectively, to prevent the shoes 60 from being pushed by the springs 61 out of engagement with the arms 26 and retainer plates 64, in the absence of work strips Y under the chain 22.

The commercial form of the machine has been illustrated and described, but it will be understood that various modifications as to details of construction, combinations and arrangement of parts, may be made within the spirit of the invention herein disclosed and claimed.

What I claim is:

45. 1. In a machine of the kind described, a supporting frame structure, spaced hot plates supported on said frame and adapted to have work pieces passed therebetween, feeding mechanism mounted on said frame ahead of the hot plates and arranged to feed edge-glued strips in edge-to-edge contact through the space between the hot plates, means biasing the hot plates toward one another to resist feeding movements of the work and thereby cause work pieces to be forced into 55 tight edge-to-edge contact during their passage between the hot plates, means anchoring the feeding mechanism to the frame structure and against movements longitudinally of the machine, and means anchoring the receiving end portions of the 60 hot plates directly to the output end portion of the feed mechanism independently of the frame, said hot plates being not otherwise anchored against movements longitudinally of the machine, whereby the forces frictionally transmitted by 65 the work from the feed mechanism to the hot plates will be transmitted from the hot plates directly back to the feed mechanism independently of the supporting frame structure and without setting up stresses in the latter tending to 70 warp the same.
2. The structure defined in claim 1 in which the means anchoring the receiving end portion of one of the hot plates directly to the output end portion of the feed mechanism comprises a drawbar 75 pivotally connected at one end to the receiving end

portion of said hot plate and at its other end to the output end portion of the feed mechanism.

3. In a machine of the kind described, a supporting frame structure, spaced lower and upper hot plates supported on said frame structure and adapted to have work pieces passed therebetween, feeding mechanism mounted on said frame structure ahead of the hot plates and adapted to feed edge-glued work pieces in edge-to-edge contact through the space between the hot plates, said feeding mechanism comprising lower and upper endless belts adapted to frictionally engage the lower and upper surfaces respectively of the work, the lower of said feed belts running over wheels journaled in the supporting frame structure, the upper of said endless belts running over wheels that are journaled in a floating frame structure that is vertically movable with respect to the supporting frame structure, means biasing the hot plates toward one another to resist feeding movements of the work and thereby cause the work pieces to be forced into tight edge-to-edge contact during their passage between the hot plates and as a result of feeding pressure exerted thereon by the feed mechanism ahead of the hot plates, means anchoring the receiving end of the lower hot plate to the supporting frame structure adjacent the receiving end of said hot plate and the delivery end portion of the lower endless feed belt, a substantially horizontally-disposed draw arm pivotally connected to the receiving end portion of the upper hot plate at one end and at its other end being journaled on the shaft carrying the upper feed belt wheel adjacent the output end of the feed mechanism, and a substantially horizontally-disposed link pivotally connected to the supporting frame structure at one end and to said draw bar at its other end, said lower and upper hot plates being not otherwise anchored against movements longitudinally of the machine.

4. The structure defined in claim 3 in which the said anchoring means for the lower hot plate is in the nature of a draw bar anchored at one end to the receiving end portion of the lower hot plate and journaled at its other end on the shaft carrying the wheel for the lower endless feed belt that is located adjacent the output end of the feed mechanism.

5. The structure defined in claim 3 in further combination with pressure mechanism adjacent the output end of the hot plates involving spaced lower and upper friction elements adapted to engage the lower and upper surfaces respectively of the work after the work has passed the hot plates and further resists feeding movements of the work, whereby to further increase the edgewise pressure of the work pieces one against the other during their passage between the hot plates, the lower of said friction elements being secured directly to and extending from the delivery end portion of the lower hot plate, a resilient arm anchored to and extending from the upper of said friction elements and connected to the output end of the upper hot plate, and yielding means biasing the said upper friction element toward the lower friction element, whereby the forces frictionally transmitted by the work from the feed mechanism to the hot plates will be transmitted from the hot plates directly back to the feed mechanism

independently of the supporting frame structure and without setting up stresses in the latter tending to warp the same.

6. In a machine of the kind described, a supporting frame structure, spaced hot plates supported on said frame and adapted to have work pieces passed therebetween, feeding mechanism mounted on said frame ahead of the hot plates and arranged to feed edge-glued strips in edge-to-edge contact through the space between the hot plates, means biasing the hot plates toward one another to resist feeding movements of the work and thereby cause work pieces to be forced into tight edge-to-edge contact during their passage between the hot plates, means anchoring the feeding mechanism to the frame structure and against movements longitudinally of the machine, means anchoring the receiving end portions of the hot plates directly to the output end portion of the feed mechanism independently of the frame, said hot plates being not otherwise anchored against movements longitudinally of the machine, whereby the forces frictionally transmitted by the work from the feed mechanism to the hot plates will be transmitted from the hot plates directly back to the feed mechanism independently of the supporting frame structure and without setting up stresses in the latter tending to warp the same, pressure mechanism adjacent the output ends of the hot plates involving spaced lower and upper friction elements adapted to engage the lower and upper surfaces respectively of the work after the work has passed the hot plates and further resists feeding movements of the work, whereby to further increase the edgewise pressure of the work pieces one against the other during their passage between the hot plates, the lower of said friction elements being secured directly to and extending from the delivery end portion of the lower hot plate, a resilient arm anchored to and extending from the upper of said friction elements and connected to the output end of the upper hot plate, and yielding means biasing the said upper friction element toward the lower friction element.
